UNITED STATES PATENT OFFICE.

MATHIAS KNÖTGEN, OF COLOGNE, GERMANY.

AUTOMATIC FIREARM WITH STATIONARY BARREL.

993,175.

Specification of Letters Patent. Patented May 23, 1911.

Application filed June 21, 1910. Serial No. 568,152.

To all whom it may concern:

Be it known that I, MATHIAS KNÖTGEN, a citizen of Germany, residing at Cologne-on-the-Rhine, Germany, have invented new and useful Improvements in Automatic Firearms with Stationary Barrels, of which the following is a specification.

This invention relates to an automatic fire-arm with stationary barrel in which the breech block is pushed back by the gases formed by the combustion of the charge and wherein it is driven into the position ready for shooting through the medium of a spring or the equivalent thereof, which is tensioned on the back-movement of the breech block.

The essential feature of the invention lies in a spring which at the beginning opposes resistance to the return-movement of the breech block which, however when the breech block is moved back to some extent, is released, thus assisting or effecting the further return-movement of the breech block and the tensioning of the spring. This arrangement permits of opposing to the return-movement of the breech block in the beginning an appreciable resistance while avoiding any danger of said block not being completely moved back.

In the accompanying drawings, in which similar letters refer to similar parts throughout the several views, the new arrangement is represented in various forms of embodiment.

Figure 1 shows the fire-arm in longitudinal section and partly in elevation; Fig. 2 is a sectional plan thereof; Figs. 3 and 4 show the rear-end of the gun in longitudinal section, with the parts in different positions; Fig. 5 is a modification partly in section and elevation; Figs. 6 and 7 show in longitudinal section and in upper plan-view, partly in section, further modifications; Fig. 6^a a cross section on line 6^a—6^a, Fig. 6; Fig. 6^b a similar section showing the parts in different positions; Figs. 8 to 11 show the new arrangement in use with a machine gun. Fig. 8 is a longitudinal section and Fig. 9 a section in upper plan view of a part of the mechanical gun. The Figs. 10 and 11 are cross-sections taken on the planes of the lines C—D and E—F of Fig. 8.

The breech block 1 carries an arm 2 by which it is slidably guided on a bolt 3 fastened to the butt-plate. The bolt 3 is provided with a spiral spring 4 which on the

one hand bears at the rear end against the butt-plate and on the other hand against the arm 2 of the breech block and constitutes the actual closing spring. The breech block has a pin 5 carrying a roller 6, which engages the hammer 8 pivoted at 7. The pivotal point of this hammer is located below the roller 6. The hammer is engaged near its pivotal point by a firing spring 9 used for driving it from the position ready for shooting against the firing pin 13. The upper extremity of the hammer has pivotally fixed thereto, a rod 10 with an auxiliary spring 11 mounted thereon. This spring bears against a collar 12, engaging with suitable pins the slots 14 of the arm 2 of breech block 1. The arm 2 carries a tripper 15 influenced by a spring 16 that tends to maintain the tripper in the position shown in Fig. 1.

Fig. 1 shows the position of the breech block after the closing of the breech has taken place. On the driving back of the breech block by the gases formed on discharging, said block is pressed against the hammer 8 by means of the roller 6. As now the spring 11 engages a long lever-arm of said hammer, whereas the roller 6 engages a short one, a very strong force is required to overcome the resistance of the spring 11 and to turn the hammer 8. When this resistance has been overcome and the breech block has moved back by a given amount, the hammer is fully thrown over by the latter, thus allowing block 1 with the roller 6 to glide freely thereover, as shown in Fig. 3. The hammer 8 and the spring 11 can thus no longer keep the breech block from moving back; on the contrary the previously tensioned spring 11 is released and acts under assistance of the tripper 15 on the arm 2 of the block, thus effecting the rearward movement thereof and simultaneously causing the closing spring to be tensioned. When the breech block has nearly reached its rear-end position, the tripper 15 strikes against a projection 17, thus insuring its being turned in such a way, that it clears collar 12 to fully release spring 11, a disengagement of collar 12 from the rod 10 being prevented by means of abutments 18. The closing spring 4 will now advance the breech into the position shown in Fig. 4, the rear arm of tripper 15 freely gliding over collar 12 and spring 11. During this operation a complete return of the hammer 8 is prevented by pawls

- 19 and 20, pawl 20 being used as a safety-device and influenced by an arm 21 while pawl 19 is actuated by the trigger. The hammer is provided with a nose 23, with 5 which it bears against the pawls 20 and 19 as shown in Fig. 4. Before retracting the trigger, arm 21 is pushed back so that an abutment 24 thereof turns pawl 20, thus withdrawing it from nose 23 of the hammer. 10 Upon retracting the trigger, it bears with one arm 25 against a rod 26 pivoted to a lever 27. The latter bears with one arm against a projection of pawl 19, and upon the retraction of the trigger, lever 27 is 15 turned in such a manner that it depresses pawl 19. In this way spring 9 is free to swing hammer 8 toward firing pin 13 and ignite the cartridge, whereupon the operation is repeated. 20 For allowing hammer 8 to be cocked by hand after the insertion of a new cartridge-frame, arm 2 has an arm 29, carrying a roller 28 which is adapted to engage a lever 30. One arm of this lever is so bent as to 25 act first with but a small leverage against the roller, thus permitting a ready return of the hammer.
- In the modification shown in Fig. 5, hammer 8 is rotatable on an arm 33, pivoted at 30 32. By this arrangement the roller 6 carried by breech block 1, engages the hammer directly above the pivot thereof with the result of opposing a resistance as large as possible to the cocking movement of the 35 hammer. The roller may be so arranged relative to the pivotal point of the hammer, that its lower edge is alined with said pivot, as the hammer is able to yield so as to allow the breech block with the roller 6 to glide 40 over it. The arrangement may also be such that the revolving bolt of the hammer is yieldingly mounted, so that the hammer with said bolt, may give way accordingly as soon as it is turned to such an amount that 45 the roller glides thereover.
- The fire-arm represented in Figs. 6 and 7 is provided with two barrels and is so arranged, that each barrel may be loaded automatically, with either balls or small 50 shot. The barrels are in superposition and the magazine for accommodating the cartridge-frame for the upper barrel is arranged laterally. Two breech bolts 1^a and 1^b are provided, said bolts being detachably 55 connected to arm 2. The latter carries at its forward upper end a support 2^a in which a bolt 34 is slidably and rotatably mounted. This bolt has a pair of noses 35, 35^a and is perforated as at 36 for the accommodation 60 of a spindle 37, the construction being such that the bolt may slide in its bearings but not rotate on the spindle. The spindle is mounted in a bearing 2^b of arm 2, and it carries at its end wedges 39, 39^a, while in 65 the breech bolts 1^a and 1^b corresponding cuneiform notches 40, 41 are provided. The spindle further carries a disk 38 having a pair of spaced radial tappets 38^a that straddle a pin 43 of an arm 42, pivoted to the butt-plate. This arm is provided with a small handle 45 for rotating disk 38 with the spindle 37 and the bolt 34 by means of pin 43 and tappets 38^a. In the position of the parts as shown, the bolt 34 with its nose 35 is placed opposite the firing pin 13 of the breech bolt 1^a and the inclined piece 39 of spindle 37 engages the notch 40. On discharging, the hammer 8 is moved toward bolt 34 and the latter strikes with its nose 35 against the firing pin of breech bolt 1^a. Owing to the powder-gases, formed when discharge takes place, the breech bolt 1^a is moved rearward, thereby forcing back arm 2. If the upper barrel is to be used, arm 42 is turned to move the inclined piece 39^a of spindle 37 into notch 41 and to bring nose 35^a in a position opposite the firing pin 13 of breech bolt 1^b, so that upon a discharge through the upper barrel, a shot is fired and said bolt is moved back. Between the bolt 34 and the bearing 2^b a spring 44 may be provided for returning the bolt into the former position. The butt-plate is provided with a plate or an arm 46 pivoted at 46^a, which is furnished with an extension 47, that engages the butt-plate. To the latter is pivoted a lever 48 which by a spring 49 is pressed against the shoulder 47. In the position of the arm as shown in Fig. 1, the lever with its tapering end bears against a bevel-face of the extension 47 of the arm 48, so as to prevent the latter from accidental displacement. If the gun is to be pointed, the arm is turned into the position shown in Fig. 5, so that lever 48 bears against a face 50 of the extension 47 that prevents arm 46 from being turned back. When the musket is pointed, it rests with this arm on the shoulder of the shooter, thus giving him steadiness and stability. The arm is further provided with a lug 51 used for attaching the usual carrying sling. Owing to such arrangement, the gun may readily be brought into a position ready for shooting.
- The machine gun, shown in Figs. 8 to 11 consists of a case-like body 54, slidably and rotatably supported by a suitable standard, and of a cylindrical piece 55, receiving the barrels 56. In the rear of the two barrels two breech blocks 1, 1^a movable in a longitudinal direction of the case are arranged, said blocks being provided with teeth, with which they engage a pinion 60, the arrangement being such that when one block is in the closing position, the other block is moved into the open or charging position. Behind the roller 6 of each breech block is arranged a lever or hammer 8 having pivoted thereto at its upper end a rod 10, which is shift-

able in a collar 12 rotatable on arm 2 of block 1 or 1^a, said collar supporting the spring 11, bearing against the lever 8. Here however, in contradistinction to the foregoing arrangement, the spring for advancing the breech block is dispensed with. This forward movement of either block takes place when the other block has been pushed back by means of the pinion 60. Furthermore the lever 8 is here not used for driving the firing pin, an auxiliary hammer 61 being provided for each breech block. The hammers 61 are under the influence of springs 62, against which they are turned on the rearward movement of the blocks, to clear slots 63 thereof. The hammers 61 have tangs 64 underneath which pawls 65 are arranged. These pawls engage with an arm recesses of rods 66. When during the forward movement the one or the other breech block passes with its slot 63 over hammer 61, the latter is moved upwardly into the slot 63 by spring 62, its movement being limited by the pawl 65 occupying a position opposite nose 64. When the breech block has nearly reached the final position, it strikes with the arm 2 against the rod 66 moving it forwardly and thus turning the pawl 65 to retract the latter from the nose 64. Owing to the partial release of spring 62, a further rotation of the hammer is thus produced, to force it against firing pin 13 and ignite the cartridge.

I claim:

- 35 1. In an automatic gun, a breech block having a rearwardly extending arm and adapted to be moved backward by the pressure of the exploded charge, a hammer pivoted to the gun frame and operatively engaged by the breech block, a pressure spring interposed between said arm and hammer, and means for advancing said block.
- 40 2. In an automatic gun, a breech block adapted to be moved backward by the pressure of the exploded charge, a hammer pivoted to the gun frame and operatively connected to said block, a tripper pivoted to

the block and adapted to engage a fixed abutment, a spring intermediate hammer and tripper, and a closing spring adapted to advance the block.

3. In an automatic gun, a breech block carrying a roller and adapted to be moved backward by the pressure of the exploded charge, a hammer pivoted to the gun frame and engaging the roller, a tripper pivoted to the block, a spring engaging the hammer and detachably engaging the tripper, a closing spring engaging the rear end of the block, and a fixed abutment adapted to be engaged by the tripper for disengaging the first-named spring therefrom.

4. In an automatic gun, a breech block carrying a roller and adapted to be moved backward by the pressure of the exploded charge, a hammer pivoted to the gun frame and engaging the roller, a firing spring engaging the hammer, a tripper pivoted to the block, an auxiliary spring engaging the hammer and detachably connected to the tripper, a fixed abutment adapted to be engaged by the tripper for disconnecting the spring therefrom, and a closing spring engaging the rear end of the block.

5. In an automatic gun, a pair of barrels, a pair of breech bolts adapted to be moved backward by the pressure of the exploded charge, a reciprocative arm, means for coupling either bolt to said arm, firing pins 80 slidable within said bolts, a hammer pivoted to the gun butt and operatively connected to the arm, a firing spring engaging the hammer, an auxiliary spring also engaging the hammer and adapted to offer a resistance 85 to the arm during the first stage of its rearward movement and to effect a subsequent completion of the rearward movement of the arm, a bolt between said hammer and firing pins, and means on said last named bolt for 90 operatively connecting it with either firing pin.

MATHIAS KNÖTGEN.
